John F. Rathbone, Albany, New York.
Letters Patent No 245. Dated Oct 23rd 1849.

The Schedule
referred to in these Letters Patent and making part of the same.

Be it known that I, John F. Rathbone, of the
City of Albany, and State of New York, have produced a
new Ornamental Design for an Air-tight Cooking Stove, and
I do hereby declare that the annexed and accompanying
drawing and description thereupon, is a full and accurate de-
lineation of a Stove constructed after my design.

What I claim as my production and desire to se-
cure by Letters Patent is the Combination and arrangement
of Ornamental Figures and Forms represented in the said
Drawing, making an Ornamental Design for an Air-tight
Cooking Stove.
